SAND REMOVAL FROM WELLS.

Edward B. Lagucki, Jackson, Miss., assignor to Shell Oil Company, New York, N.Y., a corporation of Delaware

Filed Nov. 14, 1960, Ser. No. 69,189

2 Claims. (Cl. 166—155)

This invention relates to a sand removal well tool adapted to be pumped up or down a string of tubing positioned in a well and pertains more particularly to a sand removal tool adapted to be pumped down a well tubing to engage and connect to the lower end of the tubing during well washing operations and subsequently be returned to the surface after the loose sand has been removed from the well.

A recent development in the oil industry is the drilling and completion of wells at an offshore location where the wellhead assembly and production control units are positioned beneath the surface of a body of water and preferably close to the bottom of the body of water. With wellhead assemblies positioned on an ocean floor, a hazard to the navigation of boats in offshore waters is removed. Additionally, considerable savings are realized in that it is not necessary to erect a protective stationary platform around the wellhead in the manner in which they are employed to protect well casing and wellhead assemblies extending above the surface of the water. It has also been found necessary to position a wellhead assembly on the ocean floor in water depths where it is not feasible to erect the stationary platform around a wellhead assembly.

However, the placement of wellhead assemblies on the ocean floor raises a new set of problems with regard to carrying out workover operations, maintenance and other operations in a completed well. Major workover operations call for the use of a barge positioned on the surface of the water above the well together with equipment for going down and entering the wellhead assembly and the tubing or casing string connected thereto, and in some circumstances may result in the entire removal of the wellhead assembly to the surface during workover operations. In order to carry out some of the more simple workover or maintenance operations, such as perforation of well casing, the opening of a packer, the removal of a valve, the cleaning of paraffin from a tubing string, the cleaning of sand from the well casing, etc., it has been necessary to develop an entirely new line of well tools which can be pumped through a production tubing string from some remote location, often times a mile or more from the well, and enter the well, passing down the tubing string therein to be subsequently positioned therein for carrying out some preselected operation. After completing the operation, the tool in the tubing string within the well is subsequently removed, generally and preferably by reverse circulation of fluid within the well.

One of the most pressing problems in wells in many areas is the periodic removal of sand which accumulates at the bottom of the well casing or at other levels therein. In areas where the wellhead assemblies are located on land, sand can be removed by various methods and pieces of equipment such as by running a bailer down to the bottom of the well on a wire line and bailing the sand out, or by dropping a tubing extension pipe down the well, circulating the sand out of the bottom thereof, and then retrieving the tubing extension member by means of a wire line. The use of bailing equipment has the drawback that many trips of the bailer must be made to remove the sand and it is not possible to circulate a bailer down through the tubing string with fluid pressure. In dropping an extension tail pipe down a tubing string to wash the sand from the well, a problem is encountered in reversing the circulation as the tail pipe extension nor-

2

mally buries its lower end in the sand so that the sand cannot be readily circulated up the tubing string. Additionally, tail pipes of this type cannot be circulated through a tubing string.

5 It is therefore a primary object of the present invention to provide sand removal apparatus adapted to be pumped down a well tubing string and engage the lower end thereof during sand removal operations, while being readily adapted to be disengaged from the bottom of the 10 tubing string and circulated up the tubing string at the end of the wash-out operations.

A further object of the present invention is to provide a sand removal apparatus adapted to be pumped down a well tubing with a flexible portion of the apparatus being 15 discharged from the lower end of the tubing string to seat in an operative manner on the sand accumulation within the well casing and to move downwardly within the well casing on top of the sand as the sand is washed out of the well.

20 Another object of the present invention is to provide an apparatus adapted to be pumped down a well tubing string to seat at the lower end thereof so as to permit the removal of sand from the well casing either by normal or reverse circulation.

25 A still further object of the present invention is to provide a sand removal apparatus for wells adapted to be pumped down a well tubing string running along an ocean floor and curving downwardly into a well.

Still another object of the present invention is to provide 30 a sand removal apparatus adapted to be filled with a fluid under pressure while the apparatus is being pumped down through a well tubing into position for sand removal operations.

These and other objects of this invention will be understood 35 from the following description taken with reference to the drawing, wherein:

FIGURE 1 is a schematic view illustrating a wellhead assembly positioned on an ocean floor;

FIGURE 2 is a diagrammatic view taken in partial 40 longitudinal cross-section, of one arrangement of a well in which the apparatus of the present invention has been installed;

FIGURE 3 is a diagrammatic view taken in partial 45 longitudinal cross-section of the well and sand removal apparatus after the tool carrier has been circulated upwardly to the surface again;

FIGURE 4 is a diagrammatic view taken in partial 50 longitudinal cross-section of the position of the sand removal apparatus of the present invention after the sand has been removed from the well and just as the tool carrier is being circulated down the tubing string to engage the sand removal apparatus;

FIGURES 5 and 5A are diagrammatic views taken in partial 55 longitudinal cross-section, of the sand removal apparatus of the present invention shown in greater detail; and,

FIGURE 6 is a schematic view taken in partial longitudinal cross-section of a latching device in its inoperative position.

60 Referring to FIGURE 1 of the drawing, a wellhead assembly is shown as being positioned below the surface 11 of a body of water and preferably on the ocean floor 12. The wellhead apparatus comprises a platform 13 secured to the top of a conductor pipe or surface casing 14 which in turn extends into the earth below the body of water and is preferably cemented therein in a conventional manner. The wellhead assembly may also be provided with two or more vertically-positioned guide columns 15 and 16 which are fixedly secured at their lower ends to the platform 13. A well casing head 17 is mounted on the top of the conductor pipe 14 with a control equipment housing 18 closing the top of the

casing head and/or any casing and tubing suspension equipment employed on the wellhead assembly, as well as the various control valves and other control equipment normally used on the top of a well of this type.

Emerging from the housing 18 are a pair of flow lines 20 and 21 which preferably bend in long sweeping curves from a vertical position down to a substantially horizontal position so that they can run along the ocean floor to a remote location where fluid from the well, and normally from other wells, is collected and metered and treated. Such a collection station may be several miles away. During the production of the well, normally only one of the flow lines 20 or 21 is employed in transporting fluid away from the well. The well may be provided with one or more strings of well casing 22 suspended within the conductor pipe 14. The flow lines 20 and 21, in the particular installation illustrated, are in communication with and form a continuation of a pair of tubing strings 23 and 24 depending within the well. However, in other installations utilizing a single tubing string, the second flow line may be in communication with the annular space between the tubing string and the adjacent well casing.

In FIGURES 2, 3 and 4, the two tubing strings 23 and 24 contained within the well casing 22 are shown as being secured at their lower ends to a suitable packer 25 having flow passages 26 and 27 therethrough of a diameter substantially equal to the tubing strings 23 and 24. If desired, short nipples 30 and 31 may be threadedly connected to the bottom of the packer 25 in axial alignment with the flow passages 26 and 27, respectively. The nipples 30 and 31 are preferably flared at their lower ends 32 and 33 to facilitate entry of an object being pulled into their lower ends.

Suitable stop elements are provided near the bottom of at least one and preferably both of the tubing strings 23 and 24. In the particular arrangement of equipment shown in FIGURES 2, 3, and 4, the stop elements take the form of landing nipples 36 and 37, each nipple having a seating shoulder 38 formed on the inner wall thereof for stopping any tool of slightly larger diameter from passing the shoulder 38 and dropping out the end of the tubing string.

The well casing 22 of FIGURES 2, 3, and 4 is shown as being closed at its lower end by a cement plug 40 and being provided above the plug 40 with a series of perforations 41 through the wall of the casing 22 opposite a producing formation. Positioned above the perforations 41 in the well casing 22 of one particular well installation is the packer assembly 42 adapted to close the well casing. The packer assembly is provided with a flow passage 43 therethrough with a guide cone 44 formed at the top of the flow passage 43 for guiding sand removal apparatus or other equipment therethrough. The bottom of the packer assembly 42 may be provided with a nipple 45 which may contain a ball check valve or a bottomhole choke (not shown) which may be readily removed by a suitable tool.

In order to carry out sand removal operations within a well casing of a well which has been drilled and completed underwater, a sand removal tool in accordance with the present invention is provided. The sand removal tool of the present invention employs a mandrel or short tubular body member 50 (FIGURES 2 and 5A) having a shoulder 51 of a diameter small enough to pass through the tubing string 23 yet large enough to contact and be stopped by the stop element or seating shoulder 38 of the landing nipple 36. The mandrel or body member 50 may be a single short tubular member as shown in FIGURES 2-4 or may comprise two portions 50 and 50a (FIGURE 5A) which are connected together preferably by means of a flexible joint 52. As shown in FIGURE 5A, the lower end of the mandrel of body member 50a is connected to the top of a flexible small-diameter hose 53 which may be of any necessary length, say from

1 to 20 feet, needed to carry out sand removal operations from a well. The flexible hose 53 may be made of any desired material but a suitable rubber or plastic material is preferred to make the apparatus light in weight and flexible enough to pass around a short radius bend, say four feet, in a well production string.

Secured to the lower end of the hose 53 is any suitable bidirectional valve which may be spring-loaded or which may take the form of a shear disk 54 which is preferably made of a frangible material so that it will disintegrate under pressure and the pieces will not clog the equipment in the well. The shear disk 54 is replaceably mounted in a two-piece housing 55 having ports 56 therein for permitting the escape of fluid therefrom. If desired, a perforated closed end nipple 57 may be secured to the lower end of the shear disk housing 55, the perforations 58 therein permitting the flow of fluid therefrom or thereto. The lower end of the hose 53 is provided with a bidirectional valve or shear disk 54 so that during the time when the present apparatus is being run through a tubing string into the well the hose section 53 will be full of liquid so as to increase its rigidity somewhat and facilitate pushing it through a tubing string.

In order to propel the mandrel or body member 50 and its attached hose 53 through a well tubing, a tool carrier of any suitable type may be connected to the upper end of the body mandrel 50. A preferred design of the tool carrier is shown in U.S. Patent No. 3,052,302. The tool carrier comprises a central mandrel 71 and 72 connected together by a flexible joint 73. Mounted on the central mandrel 71-72 are a pair of sealing elements or packers 74 and 75 which are held thereon by suitable sealing-elements or packer-retaining cups or rings 76 and 77, 78 and 79, respectively. The sealing elements 74 and 75 and their retaining cups 76, 77, 78 and 79 are held in position on the mandrel 71-72 by retaining nuts 81 and 82. Preferably, the mandrel 71-72 is provided with a flexible linkage, such as a ball-and-socket joint 73, at a point between the sealing elements 74 and 75 so as to facilitate movement of the tool carrier in curved sections of a well tubing or pipe.

Since the possibility always exists that any tool attached to the tool carrier may become stuck in a well, the tool carrier is preferably provided with a fishing head 83 whereby a retrieving tool (not shown) may be run through the tubing string 23 (FIGURE 5) to latch onto the fishing head 83, thereby permitting removal of the tool carrier and the body mandrel 50 and hose 53 connected thereto. The retrieving tool may take the form of another tool carrier having latching means carried at its lower end to connect onto the fishing head 83 of the tool carrier stuck within the well. As illustrated, the packer retaining elements or cups 76 and 77 surround the ends of the packer or sealing element 74 while at the same time being axially spaced from each other on the central mandrel 71 so that the packer element 74 is against, or may be expanded against, the inner wall of a tubing string 23 to form a seal thereagainst. Preferably, the sealing elements 74 and 75 are formed having an internal diameter slightly larger than that of the mandrel 71-72 so that undercut portions or annular spaces 84 are formed between the mandrel and the sealing element.

Fluid ports 86 and 87 are provided through the walls of the packer retaining cups 76 and 78 near the close ends thereof so that fluid passageways are formed through the packer retaining cups in communication between the spaces outside the packer and the annular spaces 84. The packers or sealing elements 74 and 75 are made of any suitable inflatable resilient material, such as rubber, synthetic rubber, rubberized fabric, or certain plastic materials which may be expanded under the application of a pressure fluid. The portion of the sealing elements 74 in contact with the inner wall of the tubing string may have a thickened cross-section so as to provide for some wear on the seal as it is propelled through the tubing. In addition,

the sealing elements 74 may be bevelled to substantially a point, as illustrated, if desired.

During use of the tool carrier of FIGURE 5, a pressure fluid enters ports 86 and flows into the annular space 84 within the packer element 74 so that the packer element 74 is forced against the inner wall of the tubing string thus causing the packer element to act as a piston and be forced downwardly through the tubing string by application of continued pressure from above. This action takes place since a pressure differential exists across the upper sealing element 74 whereas no pressure differential exists across the sealing element 75 on downward travel of the tool carrier, since the fluid pressure on either side of the lower sealing element is the same and there is therefore no tendency for the sealing element 75 to expand against the wall of the tubing. Thus it may be seen that, on the downward travel of the present tool carrier, the upper sealing element maintains a tight fit against the tubing at all times, while the lower sealing element 75 merely acts as an inoperative piston which would not contact the tubing wall with any force to form a seal thereagainst and hence would not be subject to wear as the tubing carrier passes downwardly through the tubing string.

In returning a tool carrier, with or without its accompanying sand removal body member 50 and hose 53, to the top of a well, circulation of the driving fluid in the tubing string 23 is reversed so that the pressure fluid would move upwardly through it. Thus, the action of the sealing elements 74 and 75 would be reversed with the sealing element 75 acting as the piston and the sealing element 74 acting as a follower. It is apparent that the present tool carrier would be operative even if the position of the sealing elements 74 and 75 were reversed.

The tool carrier is also provided with a longitudinal flow passageway, preferably in the form of an axial bore 90. A spring-loaded check valve 91 is preferably positioned in the bore 90 within the tool carrier, the valve 91 being adapted to open preferably at a greater pressure than that needed to expand the sealing element 74 against the wall of the tubing. The lower portion of the mandrel 72 is also provided with a bore 92 which communicates with the bore 90 in the upper mandrel 71 through a flow passage or bore 93 in the flexible joint 73. The flexible joint 70 in turn is provided with a flow passage (not shown) so that the interior of the body member 50 and the hose 53 is subjected to upstream pressure within the tubing string when the pressure fluid passes the check valve 91. The flexible joint 52 is also provided with a flow passage 95. By maintaining pressure fluid within the flexible hose 53 during the pumping of the apparatus down a well tubing string, sufficient rigidity is imparted to the hose 53 to prevent it from hanging up as it passes through curved sections of the flow line or well tubing 21 as shown in FIGURE 1.

In running the sand removal body member 50 and hose 53 into the well, it is apparent that the tool carrier may be merely in free contact with the top 59 of the housing 50. However, preferably the lower end of the running tool or its flexible joint 70 (FIGURE 5) has attached to the lower end thereof a suitable latching tool adapted to be disconnected from the body mandrel 50 after the body mandrel has been run into place on shoulder 51 (FIGURE 5A). A preferred form of latching device comprises a probe-like cylindrical element 60 having an axial fluid passageway 61 therethrough. The probe-like element 60 is threadedly secured to the bottom of a running and pulling mechanism in the form of a generally cylindrical body 62 having a split locking ring 63 carried on a downwardly and outwardly tapered shoulder 64 formed on the outside of the mechanism. Just below the tapered shoulder 64 is a slidable ring 65 pinned in place by shear pins 66 to the body 62 of the mechanism. A retaining ring 67 is provided for holding the shear pin ring 65 on the mechanism after the shear pin 66 has been sheared. The diameter of the shear pin ring 65 is

slightly greater than that of the tapered shoulder 64 so that on being forced downwardly the locking spring ring 63 will contact the top of the shear pin ring 65. The probe 60 is designed to slip through the bore 39 of the body member 50 to engage latching dogs 68 and 69 carried by the housing 50 which are pivotally arranged on the housing for outward movement into an annular recess 94 within the landing nipple 36. The latching dogs 68 and 69 are pivoted at a point above the lower ends thereof which permits the inner surface of the lower end of each dog to contact the outer surface of the probe 60 so that the dogs are upwardly directed.

In the use of the apparatus of the present invention, the entire apparatus comprising the tool carrier with sealing elements 74 and 75, the latching device 62, and body member 50 and the hose 53 are connected together and inserted into the flow line 21 (FIGURE 1) at a distant point, such for example, at a production platform or from an installation on shore. A source of pressure fluid (not shown) is connected to the flow line 21 in back of the tool which has been inserted in the line and the fluid is pumped through the line 21 in back of the tool carrier and sand removal apparatus of the present invention until it has passed over the curved section of the flow line and enters the wellhead assembly where it passes down the tubing string 23. The tool carrier and its sand removal body member 50 and hose 53 continue to pass down through the tubing string 23 until the body member 50 seats in the landing nipple 36, which action is ascertained at the surface by build up of pressure in the line. The equipment at that time takes the position shown in FIGURE 2 of the drawing with the flexible hose 53 dropping out the end of the nipple 30 and coiling up within the casing 22 on the sand 95 which has accumulated on top of the packer 42. During the pumping operation the check valve 91 (FIGURE 5) in the top of the tool carrier opens allowing pressure fluid to be pumped through the tool carrier, latching device and into the hose section 53. The pressure fluid within the hose is contained therein by means of the valve or shear disk 54. The rupture pressure of the disk 54 is selected at a pressure exceeding the normal pumping pressure employed to pump the apparatus down the well. In a relatively large diameter chamber such as the interior of a casing string 22 (FIGURE 2) the hose 53 can bend in a serpentine configuration when it is pushed toward an obstruction such as an area of sand built up as indicated at 95. At the time the lower shoulder or bottom 51 of the body member 50 seats on the internal shoulder 38 of the landing nipple 36, the locking dogs 68 and 69, which are spring-loaded to expand outwardly, expand into annular recess 94, locking the body member 50 in the landing nipple 36.

After the assembly has been landed as shown in FIGURE 2 of the drawing, an increase in pump pressure causes the pressure fluid to rupture the shear disk 54 (FIGURE 5A) thus allowing fluid to flow down the tubing 23 through the apparatus and hose, to be discharged out openings 56 or 58 (FIGURE 5A) in the lower end 60 of the hose and circulated up the other tubing string 24, or up the annular space between the tubing string 23 and the well casing 22 in the event that a second tubing string is not employed. Sand removal from the casing may be carried out by continued circulation of fluid down tubing 23 and up tubing 24. However, sand removal may take place in the following manner. After the fluid circulation path has been established, reverse circulation is brought about in a conventional manner with the fluid flowing down tubing string 24 (FIGURE 2) into ports 56 and 58 at the end of the hose 53 and then up through the apparatus and tubing string 23.

On reversing circulation so that the pressure fluid flows down tubing 24 and up tubing 23, the running tool having sealing elements 74 and 75 and the probe 60 are extracted from the body member 50 in the following

manner as the body member 50 is held into position by dogs 68 and 69. Upward pressure fluid forces the body 62 of the latching mechanism (FIGURE 5A) upwardly until the locking spring ring 63 contacts a shoulder 96 at the top 59 of the body member 50. As the body 62 of the latching mechanism continues to move upwardly, the split ring 63 is forced down the tapered shoulder 64 until it contacts the top of the shear pin ring 65. An increase in the fluid pressure causes the shear pins 66, which are preferably bronze or some other soft metal in this operation, to shear and the shear pin ring 65 is forced downwardly allowing the split ring 63 to move downwardly off the tapered shoulder 64 and contract to a smaller diameter below the shoulder so that it can be pulled out of the top 59 of the body member 50. With the latching assembly 62 and probe 60 free of the housing 50 these elements move upwardly through the tubing 23 with the tool carrier where this portion of the apparatus can be retrieved at, for example, a well platform manifold.

Continued reverse circulation of fluid down tubing 24 and up tubing 23 entrains the sand 95 which enters the lower end of the hose 53 and is circulated to the surface. As the sand build-up 95 (FIGURE 2) erodes away, the pull of gravity causes the hose to move downwardly on top of the sand and elongate until finally it falls through the opening 43 in the packer 42 and down into the open casing opposite the perforation 41. With the hose extended in this manner, as shown in FIGURE 4, the fluid flowing down the tubing 24 flows down through the annular space between the hose 53 and the wall of the bore 43 through the packer 42. Sand clean out below the packer 42 is continued if desired all the way down to the cement plug 40 by employing a hose of suitable length.

When the fluid returning to the surface through tubing 23 indicates that all the sand has been removed the body member 50 and hose 53 may then be removed by pumping a tool carrier down the tubing string 23, as shown in FIGURE 4, the tool carrier being provided with an engaging tool at its lower end for latching onto the body member 50 and retracting its locking dogs 68 and 69. As shown in FIGURE 6, the only difference between the retrieving mechanism and that employed to place the body member 50 in place originally is that a large-diameter probe 97 is employed so that the locking dogs 68 and 69 of the housing member 50 are retracted out of the annular recess 94. Also in the case of retrieving the tool, the shear pins 66 (FIGURE 5A) are made of steel instead of a soft metal so that they will not shear. Thus, when circulation is reversed so that the locking spring ring 63 is forced upwardly in contact with shoulder 96, a continued application of fluid pressure raises the entire body member 50 with its retracted dogs 68 and 69 (FIGURE 6) out of the landing nipple 36 along with the hose and the entire apparatus is circulated up the tubing string 43 where it may be retrieved. It is to be understood that the normal diameter of the split ring 63 is of a size to contact the shoulder 96 when moved against it in an upward direction. At the same time the split 63 may be contracted sufficiently to pass shoulders 96 on moving downwardly therethrough. The retrieving probe 97 need not be provided with a fluid passage 98 therethrough, if desired.

I claim as my invention:

1. A sand removal well tool adapted to be pumped

down a small-diameter pipe string within a well, said string of pipe having a lower open end and stop means positioned therein to prevent the passage of a well tool therethrough, said well tool comprising a body member having an axial bore therethrough, said body member being of a diameter small enough to pass through the small-diameter pipe string in the well and be stopped by said stop means of said pipe string, a pumpable tool carrier adapted to be connected and disconnected to the top of said body member by applying pressure fluid pumped through said pipe string, longitudinal fluid passage means in said tool carrier in communication with the axial bore of said body member, unidirectional valve means in said passage means preventing fluid from being pumped upwardly through the tool carrier as it is being pumped upwardly out of the well, first retractable latching means carried by said tool carrier for connecting to said body member near the top thereof, second retractable latching means carried by said body member for connecting to the pipe string near the lower end, an elongated section of flexible hose secured to the lower end of said body member and in fluid communication with the axial bore thereof, and valve means secured to and normally closing the lower end of said hose during pumping-in operations.

2. A sand removal well tool adapted to be pumped down a small-diameter pipe string within a well, said string of pipe having a lower open end and stop means positioned therein to prevent the passage of a well tool therethrough, said well tool comprising a short tubular body member having an axial bore therethrough, said body member being of a diameter small enough to pass through the small-diameter pipe string in the well and be stopped by said stop means of said pipe string, stop means carried by said body member for engaging the stop means of said pipe string, a pumpable tool carried adapted to be connected and disconnected to the top of said body member by applying pressure fluid pumped through said pipe string, longitudinal fluid passage means through said tool carrier in communication with the axial bore of said body member, unidirectional valve means in said passage means preventing fluid from being pumped upwardly through the tool carrier as it is being pumped upwardly out of the well, first retractable latching means carried by said tool carrier for connecting to said body member near the top thereof, second retractable latching means carried by said body member for connecting to the pipe string near the lower end thereof above the stop means therein, an elongated section of flexible hose secured to the lower end of said body member and in fluid communication with the axial bore thereof, bi-directional valve means secured to and normally closing the lower end of said hose during pumping-in operations, and a perforate screen element carried at the end of said hose below said bi-directional valve means.
